UNITED STATES PATENT OFFICE.

GRIDLEY ADAMS, OF CHICAGO, ILLINOIS.

IRONING-BOARD.

1,357,017.

Specification of Letters Patent. Patented Oct. 26, 1920.

Application filed January 12, 1920. Serial No. 350,808.

To all whom it may concern:

Be it known that I, GRIDLEY ADAMS, a citizen of the United States, residing at Chicago, in the county of Cook and State 5 of Illinois, have invented certain new and useful Improvements in Ironing-Boards, of which the following is a specification, reference being had to the accompanying drawings, forming a part thereof.

10 The purpose of this invention is to provide an improved construction of an ironing board and the like with folding legs. It consists in the elements and features of construction shown and described as indicated in the claims.

15 In the drawings:

Figure 1 is a side elevation of an ironing board equipped according to this invention, the same being shown in erected 20 position for service.

Fig. 2 is an inverted plan view of the board with the legs extended as when in use.

Fig. 3 is an inverted plan view of the 25 board with the legs folded up against it as when out of service.

Fig. 4 is a detail section at the line, 4, 4, on Fig. 3.

In the structure shown in the drawings 30 the ironing board or ironing table top member is shown at A, and this member is hereinafter referred to as the "board." To the under side of the board, A, there are hinged at a comparatively short distance from the 35 wider end of the board at the under side thereof at approximately the same transverse line, and conveniently by means of the same pivot support, a, a support consisting of two legs, B, B, constituting the 40 support of one end of the board, and two diverging members, C, C, of a unitary leg which extends obliquely longitudinally of the board and constitutes support of the opposite end of the board, being adapted 45 to thus support said opposite end by means of a brace member comprising the two arms, D, D, which are connected together by means of a cross-tie, D¹, the three parts constituting a unitary structure moving together as a single brace for the two arms, 50 D, D, of said support. This brace member having its arms connected together, and pivotally connected at one end as stated to the support, C, C, has the other ends engaged in slideways, F, F, fastened to the under side of the board, permitting the T

cross-heads, d, d, of said arms, D, D, to slide toward the end at which the supports, B, B, are pivoted as described, for permitting the supports, C, C, to fold up against 60 the under side of the board, said slideways having stop shoulders, f, at the other end of the course for engaging said T cross-heads to stop them from sliding and cause the brace to hold the support, C, C, in extended position for supporting the board. The guard or retainer of the slideway is a spring, F¹, which operates against the cross-head to force it into engagement with the shoulder when the cross-head reaches 65 the position at which the support is properly extended; and the slideway ends, by the spring guard being formed as a loop, f¹, just beyond the shoulder, f, so that the support, C, C, cannot swing too low or out 70 of range for functioning for support. For releasing the brace to permit the supports, C, C, to be folded up against the under side of the table, the operator lifts the ends of the table to relieve the pressure upon 75 the support, reaches under the table and disengages the brace arms, D, D, from the shoulders, f, and holding the brace thus released, brings the support again to the floor, which will cause the cross-heads to 80 slide away from the shoulders, and thereupon the support can be folded up completely against the under side of the board.

The legs, B, B, have their pivots, b, b, slightly oblique to the length of the boards 85 so that in swinging from position folded up against the under side of the board down to operative position, the legs swing also outwardly so that they diverge when resting upon the floor to support the board. 90 For controlling the operation of the legs there is provided a controlling lever, H, H, fulcrumed on the under side of the board at a line considerably outward from the transverse line at which the legs, B, B, are 95 pivoted to the board, said controlling lever being conveniently constructed with two diverging arms to extend between and approximately parallel to the position of the two legs, B, B, when the latter, as well as 100 the lever are folded up against the under side of the board as seen in Fig. 3. These two arms of the controlling lever are connected respectively by links, L, L, with the two legs, B, B, the lengths of the connecting links and the positioning of their pivotal connections on the lever arms and the 105 110

legs respectively, being such as to adapt said three elements,—that is to say, the legs, the lever arms and the links,—to fold up substantially flat against the under side of 5 the board as seen in Fig. 3. These parts may be thus dimensioned so as to cause the lever, H, to extend in a plane substantially parallel to the plane of the supports, C, C, at operative position—that is, in position 10 of supporting the board for use. This is a preferential but not an absolutely essential relation of the part. The lever extends inward beyond its connection with the links, L, L, for connection, by means of links, 15 M, M, with the two diverging members of the support, C, C; and when the several parts are dimensioned relatively as above described, so that the lever extends substantially parallel to the inclined direction 20 of the supports, C, C, at board-supporting position, the links, M, will extend substantially parallel to the board at said supporting position of the legs. The dimensioning of the parts and their connections as de- 25 scribed it will be seen will permit the supports, C, links, L, and the lever, H, to fold up substantially flat against the under side of the table.

Upon considering this structure it will 30 be seen that the entire supporting structure can be folded up against the under side of the board by manipulation of the supports at either end upon releasing the brace, D, D, in the manner above described, and that 35 at supporting position of the supports, C, when braced by the engagement of the brace, D, D, with the stop shoulders, f, on the slideways, F, the connection between the two supports afforded by the control- 40 ling lever and links, M, M, described, causes the legs, B, B, to be definitely fixed in their outspread or board-supporting position, and that the load resting upon the legs tends to tighten and secure all the parts in board- 45 supporting position.

I claim:—

1. In a device for the purpose indicated, in combination with a board, a support for one end hinged to the board for folding up 50 against the under side thereof, and means for stopping it in down-swung or board-

supporting position against folding up; a support for the other end hinged to the board for folding up in the same direction as the first mentioned support; a control 55 lever pivoted to the board at a point longitudinally outward from the hinge connection of the second support; a transmitting link connecting said control lever to the second support, said link being dimensioned 60 and the points of connection thereof to the lever and support respectively being positioned relatively to permit said three connected parts to fold up substantially flat at the under side of the board; the control 65 lever being extended beyond the hinge connection with the transmitting link, and a link connected at one end to said lever ex- 70 tension and at the other end to the first mentioned support, the distance between the pivot to the board of the lever and the first mentioned support plus the distance from the said pivot of the support to the pivot thereto of the last mentioned link being sub- 75 stantially equal to the sum of the lengths of said last mentioned link and the lever, whereby said lever link and support may be folded up substantially flat against the under side of the board.

2. In the construction defined in claim 1, 80 a second support comprising two laterally separated legs, each separately hinged to the board, the controlling lever being a unitary member and the transmitting links being duplicated for connecting the two 85 legs respectively with said unitary controlling lever, whereby the controlling lever causes the two laterally separated legs to operate together for folding and unfolding.

3. In the construction defined in claim 1, 90 foregoing, the second support comprising two laterally separated legs, having their hinge pivots oppositely oblique to the length of the board, the controlling lever being a unitary member and the transmitting links 95 being duplicated for connecting said unitary member with the two laterally separated legs respectively.

In testimony whereof, I have hereunto set my hand at Chicago, Illinois, this 9th 100 day of January, 1920.

GRIDLEY ADAMS.
